UNITED STATES PATENT OFFICE.

ST. JULIAN GIRARDEAU, VIRGINIUS DAVIS THOMPSON, AND ROBERT LYLES BEAL, OF GALVESTON, TEXAS.

SEWING-MACHINE ATTACHMENT.

SPECIFICATION forming part of Letters Patent No. 624,644, dated May 9, 1899.

Application filed December 27, 1898. Serial No. 700,477. (No model.)

To all whom it may concern:

Be it known that we, ST. JULIAN GIRARDEAU, VIRGINIUS DAVIS THOMPSON, and ROBERT LYLES BEAL, citizens of the United States, residing at Galveston, in the county of Galveston and State of Texas, have invented a new and useful Sewing-Machine Attachment, of which the following is a specification.

This invention relates generally to sewing-machines, and more particularly to a motive power for operating the said machine, the object being to provide an exceedingly cheap, simple, and efficient hand-power which can be used independent of or in conjunction with the foot-treadle.

Another object of the invention is to provide a mechanism which can be applied to any of the sewing-machines now in use and can be adjusted to suit the various sizes of machines.

With these objects in view our invention consists, essentially, of a clamp adapted to be attached to the table of the sewing-machine, an adjustable lever pivoted to said clamp, and a pitman adapted to be connected to the drive-wheel of the machine and adjustably connected with the lever, the reciprocation of said lever causing the rotation of the drive-wheel.

The invention consists also in certain details of construction and novelties of combination, all of which will be fully described hereinafter and pointed out in the claim.

In the drawings forming part of this specification, Figure 1 is a view showing the end elevation of a machine provided with our attachment. Fig. 2 is a detail view of the operating-lever. Fig. 3 is a detail view of the clamp to which said lever is pivoted. Fig. 4 is a sectional view of said clamp, and Fig. 5 is a sectional view on the line 5 5 of Fig. 2.

In carrying out our invention we employ a clamp-bracket A, essentially in the shape of an open rectangle and having a set-screw A' working through one member thereof, the inner faces of the members and the set-screw being covered with rubber or other suitable material A², the surface of which is rough-

ened in order to bind tightly upon the edge of the machine-table when said bracket is clamped thereto, as shown in Fig. 1. The 50 bracket is slotted at one corner, as shown at A³, and upon each side of said slot are the pivot-lugs A⁴, between which is inserted the bearing portion B², formed upon the end of the section B' of the lever B, and the said lever is pivotally connected to the bracket by means a pin or bolt B³, passing through the lugs and the bearing B² upon the end of the section B'. The sections B' and B⁴ of the lever are adjustable upon each other, 60 as shown in Figs. 1 and 2, the section B' having a loop B⁵ formed integral therewith, which embraces the section B⁴, and has a set-screw B⁶ passing therethrough to engage the section B⁴. This section B⁴ is also formed with 65 a loop B⁷ integral therewith and which embraces the section B' and has a set-screw B⁸ passing therethrough to bear upon the section B'. By this means the sections B' and B⁴ can be adjusted longitudinally upon each 70 other in order to make the lever long or short, as desired. The lever is provided with a handle C, and adjacent thereto is slotted longitudinally, as shown at D, said longitudinally slotted portion having a series of perforations 75 D', through which a pivot-pin is adapted to be passed for the purpose of connecting the pitman E thereto, the opposite end of said pitman being connected to the drive-wheel F, as most clearly shown in Fig. 1. By working 80 the lever up and down the drive-wheel is operated through the medium of the pitman, and in this manner the machine can be operated by hand instead of foot power, and this mechanism can be used either independent of or in 85 conjunction with the ordinary foot-treadle. By having the lever adjustable and also providing for the adjustment of the pitman we are enabled to apply and operate our pitman upon any of the various machines now in use. 90

Having thus fully described our invention, what we claim as new, and desire to secure by Letters Patent of the United States, is—

A sewing-machine attachment, comprising

a bracket adapted to be secured to the table of the machine, a lever pivoted to said bracket, said lever being composed of two sections adjustable upon each other, each section having a loop adapted to embrace the other section, and a set-screw passing through each loop, the outer section of said lever being slotted longitudinally and a pitman adapted to

be adjustably secured in the said slotted portion, substantially as shown and described. to
ST. JULIAN GIRARDEAU.
